PRINTING MECHANISM

Frank J. Furman, Endicott, and Edward J. Rábenda, Binghamton, N. Y., assignors to International Business Machines Corporation, New York, N. Y., a corporation of New York

Application October 25, 1941, Serial No. 416,508

6 Claims. (Cl. 101—93)

This invention relates to record controlled machines in general and more particularly to printing mechanism for such machines.

The broad object of the invention is to provide an improved printing mechanism which is simpler, more flexible and capable of more divergent uses than former printing mechanisms.

A more specific object of the invention is to provide individual tripping instrumentalities for a plurality of printing hammers in the form of magnets together with a flexible plugging arrangement by means of which printing may be effected or suppressed in any selected orders and during any printing operations to produce results not heretofore obtainable in such machines.

With the use of the present invention conditions for printing or suppressing printing may be preset in accordance with particular requirements for one section of the type carriers and further conditions for printing or suppressing printing may be preset in accordance with other requirements for another section of the type carriers so that both settings may concurrently control their respective sections without either affecting the operation of the other.

A still further object is to provide improved electrical control of the printing of zeros from the type carriers.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a vertical section of the essential mechanism of the printing section of a tabulating machine showing the arrangement of the improvements of the present invention.

Fig. 2 is a section taken on lines 2—2 of Fig. 1.

Figs. 3 and 3a taken together and placed one above the other constitute a simplified circuit diagram showing the relationship of the new devices with the prior machine.

Fig. 4 is a sample of a record showing the various printed results obtainable.

Fig. 5 is a timing diagram of the essential circuit controlling devices.

Fig. 6 is an enlarged view showing the type bar in zero printing position.

The type bars or carriers with which the invention is coordinated may be of any form in which the carrier is differentially positioned but for purposes of disclosure I prefer to show the invention as applied to an improved form of

printing mechanism such as disclosed in the pending application of A. W. Mills, Serial No. 415,860, filed October 21, 1941.

In the present case enough of such proposed printing mechanism is shown to enable an understanding of its operation.

It includes the usual platen 10 (Figs. 1 and 6) and a number of vertically reciprocable type bar assemblies, each including a carrier 12 on which is mounted a type head 13. Each type head has type elements 14 adapted to print the numerals 1 to 9 and the letters of the alphabet. Below the type elements 14 are two zero type elements 14a, which are separated from each other by a space as shown.

The bars 12 are moved upwardly by mechanism similar to that claimed in Patents Nos. 2,016,632 and 2,131,918, granted to A. W. Mills on October 8, 1935, and October 4, 1938, respectively.

20 The bar 12 is moved upwardly by a cam operated shaft 21 which carries arm 22 having depending link connection 23 with a bail 24 pivoted at 25. Also pivoted at 25 is an actuating arm 26 which is connected at its left end to bar 12 through a link connection 27. Arm 26 is urged in a clockwise direction by a spring 28 which is connected at its upper end to a crossbar secured to arm 22. Thus as the arm 22 and bail 24 are rocked clockwise by shaft 21, the spring 28 will rock arm 26 25 in the same direction and cause elevation of type bar 12.

The bar 12 is provided with a set of teeth 29, one tooth for each of the digits 0 to 9, and a further set of teeth 30. Cooperating with teeth

35 29 is a stop pawl 31 normally held out of the path of the teeth by the armature of a magnet 32. Similarly cooperating with teeth 30 is a stop pawl 33 normally held out of the path of the teeth by the armature of a magnet 34. Magnets 32 and pawls 31 are carried by a frame 35 which is mounted for vertical reciprocation and the joint action of pawls 31 and 33 causes selective positioning of the bar 12 to stop the same during its upward movement so that one of the type elements is presented to the printing line opposite platen 10.

The particular manner in which type bars are positioned for printing forms no part of the present invention, so the same needs no further detailed explanation.

Adjacent to each bar 12 is a lever 36 pivoted at 37 to a cross bar 38 (see also Fig. 6). With the type bar positioned to present any but its two lowermost elements 14a to printing position, the lever 36 remains in the position shown in

Fig. 1. When the bar is positioned to present either of the zero type elements 14a to printing position a block 39 secured to the bar will be in elevated position where it engages lever 36 and rocks it clockwise to the position of Fig. 6 to open a pair of normally closed contacts 40 and close a pair of normally open contacts 41.

Adjacent to and in the plane of each type head 13 is a printing hammer 42 freely pivoted at 43 (Fig. 1). A lever 44 lying beside the hammer has an extension 45 engaging the hammer and a spring 46 connected to a cross bar 47. Bar 47 is supported by pivoted arms 48 lying against a flattened rod 49 which rod may be rotatively positioned to increase the tension of springs 46. The hammer 42 is normally held in the position shown by engagement thereof with a spring urged armature latch 50 of a magnet 51 carried by a cross bar 52. As seen in Fig. 2 the armature and magnets are arranged in two rows to accommodate the usual spacing of the hammers. Magnet 51 upon energization will attract its armature 50 and release hammer 42 whereupon spring 46 will rock lever 44 clockwise carrying with it hammer 42. A stopping projection 53 on the lever 44 will strike the cross bar 54 before the hammer reaches type element 14 and 14a and the hammer will continue on alone under the momentum acquired, to effect printing. Thereafter the usual restoring bail 55 will be rocked counterclockwise to restore the hammers to their latched positions.

For selectively controlling the energization of magnets 51 there is provided a plugboard panel 56 mounted on cross bar 52, on which panel are provided several rows of plug sockets which are wired as shown in Fig. 3a. For each printing column there is a vertical row of four sockets numbered 57, 58, 59 and 60 of which eighteen rows are shown for illustration. In each row the sockets 58 and 59 are electrically connected to one another and to the common blade of contacts 40, 41 through a wire 61. Each socket 60 is connected to the contacts 41 of the next adjacent columnar position through a wire 62. All the contacts 40 are connected to a common wire 63 extending to a pair of cam controlled contacts designated CF5.

The contacts CF5 are timed to close momentarily at the usual printing time, that is, when all the type bars 12 have been positioned to present selected type elements 14 or 14a to the printing line, to energize selected tripping magnets 51 in accordance with various presettings of plug connections as will now be explained.

Zero printing to the right

As usual when a type bar advances, it is stopped either in a significant character printing position or one of the zero printing positions and if it is not interrupted it will stop with the second zero type in printing position. Whether a zero is printed depends upon whether the next higher ordered type bar presents a significant character or digit. In Fig. 4 there is shown an example in a field designated "Quantity" of common item printing wherein zeros are printed under control of columns to their left. For such field, the related plugboard columns are connected as shown in Fig. 3a with plug connections 64 made in columns 1 to 4 and plug connections 65 made in columns 1 to 3. These plug connections are so called "bottle plugs" having a configuration as shown at 66 in Fig. 1. Insertion of a connection 64 couples a magnet 51 for op-

eration if the related column is set to print a significant digit. Insertion of a connection 65 couples the magnet 51 of the next lower order for operation if said lower order is set at zero and the order in which the connection 65 is made is set at some significant digit.

With the connections so made for the "Quantity" field, the type bars would be positioned for the first line of Fig. 4 to represent the number 10 5671. As explained, none of the four bars involved would disturb their related contacts 40, 41 in moving to these positions. Upon closure of contacts CF5 a circuit will then be completed from right side of current supply line 67, through contacts CF5, a plug connection 110, wire 63, contacts 40 of columns 1 to 4 in parallel, wires 61, sockets 58, connections 64, sockets 57 and magnets 51 to the left side of line 68.

When the type bars are set to print 700 for example, on the second line of Fig. 4, the bars for columns 1, 3, and 4 would be positioned at zero and the bar for column 2 at 1 so that when contacts CF5 close the above traced circuit would be completed only for column 2 since contacts 40 in columns 1, 3, and 4 are now open. The circuit for column 2 will branch however from its wire 61 through its related socket 59, connection 65, socket 60, wire 62, contacts 41 of column 3 (now closed), wire 61 of column 3, socket 58, connection 64, socket 57 and magnet 51 of column 3. The circuit through wire 61 of column 3 in turn branches through its socket 59, connection 65, socket 60 and wire 62 to contacts 41 of column 4 (now closed) and thence in the same manner through wire 61 of column 4 to energize the column 4 magnet 51.

It may be observed that if connections 65 were not made, all zero printing would be suppressed and only the significant characters printed.

40

Zero printing to the left

Fig. 4 in the field designated "Code" shows an example where it is desired to print zeros in all positions within the field capacity (columns 6-8 for example). For such result the connections 64 are made in columns 6, 7, and 8, and connections 65 are made in columns 6 and 7 with the same effect upon closure of contacts CF5 as explained above. An additional flexible plug connection 70 is made from socket 60 of column 5 to a socket 59 of column 8 or any other column in which it is known that a character will invariably be printed. With such connection 70 made, the circuit through wire 61 of column 8 which may 50 flow from the related contacts 40 or 41 will branch to socket 59, connection 70 to socket 60 of column 5, wire 62, contacts 41 of column 6 and thence to magnet 51 of that column, this circuit branching as before to also engage magnet 51 of column 7.

Selective printing control

Fig. 4 shows two fields headed "Price A" and "Price B" in which the printing is selectively controlled so that for the example chosen, printing takes place in both fields for the first operation, printing takes place in field "Price A" alone for only the fourth operation. Printing takes place in field "Price B" alone for the second and third operations and in neither field for the fifth operation.

To explain this manner of control it is necessary to briefly refer to the record card sensing mechanism of the machine shown diagrammatically in Fig. 3 wherein it is indicated that the

75

record cards R containing perforations representing the data to be printed are moved past an upper set of sensing brushes UB and then past a lower set of sensing brushes LB. The movement of the cards is synchronized with the type bar mechanism so that the bars rise as the index point positions designated 9 to 0, x and 12 pass brushes LB and are restored during the interval between cards. As the cards pass the brushes the perforations representing data to be printed are sensed by the brushes and cause energization of magnets 32 and 34 to control the positioning of the bars 12 in known manner.

When it is desired to suppress printing of data in field "Price A" from a card, that card is provided with a special perforation designated X1 in the X index point position of a selected column. When it is desired to suppress printing of data in field "Price B" a special perforation designated X2 is made in another column. Where printing in both fields is to be suppressed, both perforations are present.

As a preliminary, plug connections 71 are made between sockets 51 of columns 9 and 10 and sockets 72 and connection 73 between sockets 58 of columns 9 and 10 and sockets 74. For columns 11 and 12 connections 75 are made between sockets 57 and sockets 76 and connections 77 are made between sockets 58 and sockets 78. The sockets 72 and 74 for each column are normally electrically connected through wires 79 and 80 and a pair of contacts 81a so that in effect the sockets 57 of columns 9 to 12 are normally electrically connected and the trip magnets 51 of these columns are energized in the same manner as for the "Quantity" field. A representative circuit for column 9 for example is traceable from line 61 (Fig. 3a), contacts CF5, wire 63, contacts 40 of column 9, wire 61, socket 58, connection 73, socket 74, wire 80 (Fig. 3), contacts 81a, wire 79, socket 72, connection 71, socket 57 and magnet 51 of column 9 to line 68. With connection 65 made in columns 9 and 11 zeros to the right will be printed as for the "Quantity" field.

When a card having an X1 perforation is sensed a circuit is completed from line 67 (Fig. 3), contacts CF1, the X1 hole, brush LB to a socket 82 from whence a connection 83 extends to a socket 84, relay magnet 81 and contacts CF3 to line 68. Contacts CF3 close only at the time the X hole is sensed (see Fig. 5) and upon energization of magnet 81 it closes its contacts 81b to provide a holding circuit. Magnet 81 is of the well known double wound type having two windings, a pickup winding and a holding winding, the pickup winding being connected between socket 84 and contacts CF3 and the holding winding being connected between contacts 81b and a wire 85. Thus upon closure of contacts 81b a circuit is completed from line 67, contacts CF3, 81b, holding winding of magnet 81, wire 85 to line 68 to keep magnet 81 energized for the period indicated in Fig. 5, that is, until the zero impulse contacts CF5 have closed.

Concurrently with closure of contacts 81b, the contacts 81a open and as they are held open until after contacts CF5 close and open again, no circuits will be completed for printing in "Price A" field. In an exactly similar manner, when a perforation X2 is sensed, a magnet 86 is energized to open its contacts 86a in the print selecting magnet circuits of field "Price B" to suppress printing in that field. Obviously, if both X1 and X2 holes are present in card R, printing will be suppressed in both price fields.

Zero print suppression

In Fig. 4 the field headed "Name" is one in which it is required to print amounts with control of zero printing to the right and in which it is also desired to print alphabetic data in which no zeros are desired. To make this clearer, if this field were plug connected as for the "Quality" field, a zero would appear in the second line between the R and the S in column 14 and also in the fourth line between the M and the N. Accordingly in this field the connections 64 are made as before in columns 13 to 15 but for zero control, connections 87 and 88 are made as shown for sockets 59 and 60 of columns 13 and 14, the connection extending to sockets 89-90 respectively. Contacts 91a (Fig. 13) between which sockets 89 and 90 are wired are normally open so that no zero print circuits can be completed until these contacts are closed and only significant characters will be printed.

Cards which contain amounts for which zero printing is desired is punched with an X3 hole which upon sensing causes energization of relay magnet 91 in exactly the same manner as magnets 81 and 86 are energized. As a result contacts 81a are in closed position when contacts CF5 close so that a circuit for causing printing of the zero in column 14 of the first line of Fig. 4 will be completed as follows: From line 67, contacts CF5, wire 63, contacts 40 of column 13, wire 61, and socket 59 of such column, connection 87, socket 89, contacts 91a, socket 90, connection 88 to socket 60 in column 13, wire 62, contacts 41 of column 14 (now closed), wire 61, socket 58, connection 64 of column 14 to socket 57 and magnet 51 of that column.

It will be apparent that the connections 87, 88 instead of being made to sockets 89, 90 may be made to sockets 76 and 78 related to magnet 86 and hole X3 plug connected to control this magnet. The zero print control would then be normally effective and disabled upon sensing the X3 hole.

Group indication printing

The field of Fig. 4 headed "District" is to have printed thereon an amount or word which appears on each of a group of cards and if plug connections were made as for the "Quantity" or "Code" fields this amount or word would be repeated on each line. It is desired therefore to suppress printing for all lines except that for the first card. One way to effect this is to provide the first card with a special X hole and plug connect socket 57 and 58 of this field to normally open relay contacts as for example 91a and energize the magnet 91 from the X hole. Or conversely, provide all cards except the first with the X hole and plug connect the sockets 57, 58 as for field "Price A."

Another manner of suppressing the printing from cards after the first which does not require X punching either the first or subsequent cards may be effected as follows:

A tabulating machine to which the present invention is applied is provided with contacts which are closed during total taking operations which follow the accumulation of data from each group of record cards. These contacts are generally designated as total setting contacts in the machine and an additional contact designated TS in Fig. 3 is provided, whose time of closure is indicated in Fig. 5. When such contact closes during total taking operations (during which operations card feeding is suspended

with the first card of a group about to pass brushes LB, upon resumption of card feeding following completion of total taking operations), a circuit is completed from line 67, contacts TS, and relay magnets 94 and 95 in parallel to line 68. Magnets 94 and 95 close their contacts 94a and 95a to establish a circuit from line 67, contacts CF6, relay magnet 97, contacts 94a, a plug connection 98, contacts 95a, usual card lever contacts LCL (closed if a card is present at the brushes LB) to line 68.

Magnet 97 closes its contacts 97a to provide a holding circuit for the magnet until card feeding has resumed and contacts CF6 open after contacts CF3 close at the X hole sensing time and open again. A second pair of contacts 97b are connected by a connection 99 to a relay magnet 100 so that with contacts 97b held closed, upon closure of contacts CF3 a circuit is completed from line 67, contacts 97b, connection 99, pickup winding of magnet 100, and contacts CF3 to line 68. Contacts 100b provide a holding circuit through contacts CF4 until after contacts CF5 have closed. Contacts 100a of the magnet are wired to sockets 101 and 102 which are plug connected to sockets 57 and 58 respectively in the same manner as for field "Price A." As a result, contacts 100a are closed when the hammer trip impulse from contacts CF5 is transmitted and printing will take place. Thereafter the contacts 100a reopen and remain so during the sensing of subsequent cards until a further total taking operation ensues when contacts TS again close.

Examination of Fig. 4 discloses that the various printing requirements for the several fields may be thus variously taken care of, all at the same time so that as in the example "Quantity" may be printed from each card with zero control, "Code" may be printed from each card with zeros to the left filled in, "Price A" and "Price B" may be printed selectively and independently of each other, suppressed for designated cards, "Name" data may be printed without zero for certain cards and with zero control for others and "District" may be indicated from the first card only.

The plug connection 110 (Fig. 3a) is provided so that by manually removing this connection all printing will be suppressed as long as 110 remains removed.

While there has been shown and described and pointed out the fundamental novel features of the invention as applied to a single modification it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a machine having a type bar positionable to present type elements to a printing position, the combination of a printing hammer, a spring urging the hammer to strike a positioned type element, a latch holding the hammer, a magnet, a circuit connection therefor, a normally closed pair of contacts included in said circuit connection, means for completing said connection upon positioning of the type bar, said magnet when energized causing operation of the latch to release the hammer for movement under control of its spring and means controlled by the type bar when the bar is in a predetermined position for

75 opening said contacts to prevent completion of said circuit connection.

2. In a machine having a plurality of type bars, each positionable to present type elements to a common printing line, the combination of a printing hammer for each type bar, an actuating spring for each hammer, a latch for each hammer, a magnet for each latch for releasing the related hammer, energizing means for the magnets, selectively settable means for rendering selected magnets responsive to said energizing means when the type bars related to said selected magnets are moved to present certain type elements to the printing line, and further selectively settable means associated with each type bar for rendering another magnet whose type bar is positioned to present a type element other than said certain type elements to the printing line, responsive to said energizing means concurrently with said selected magnets.

3. In a printing machine, a plurality of differentially positionable type bars, a printing controlling magnet for each type bar, a set of positionable contacts for each bar, each set of contacts being controlled by its related bar to occupy one position when the bar is in significant digit printing position and another position when the bar is in zero printing position, selectively settable means for effecting a circuit connection between each magnet and the related contacts and means for energizing said magnets through said circuit connections and contacts for only the bars whose contacts are in their first named positions.

4. In a printing machine a plurality of type bars each positionable in several digit representing positions, a printing hammer for each, a release magnet for each hammer, energizing means for the magnets, means controlled by said bars when all are positioned to represent a significant digit or at least one is set to represent a significant digit for rendering said energizing means effective to concurrently energize all the magnets, and when both bars are positioned to represent zero for rendering said energizing means ineffective.

5. In a printing machine a type bar differentially positionable to represent the digits, a printing hammer therefor, a release magnet for the hammer, contacts controlled by the bar, energizing means for the magnet and selectively settable means cooperating with said contacts effective when set in one position to render the energizing means effective only when the bar is positioned to represent significant digits and effective when set in another position for rendering the energizing means effective only when the bar is positioned to represent a zero.

6. In a machine of the class described, a differentially positionable type carrier, record sensing means, means controlled thereby to cause positioning of said carrier, said carrier having at least two different positions, a printing hammer, tripping means therefor, means controlled by the carrier for rendering the tripping means effective when the carrier is in its one position and ineffective when the carrier is in the other position, and settable means cooperating with said last named means for controlling the tripping means whereby the tripping means is rendered ineffective when the carrier is in its one position and effective when the carrier is in its said other position.
